METHOD OF SEALING BAGS

August E. Almgren, Hillside, and John P. Jakob,
Roselle, N. J., assignors to American Can Com-
pany, New York, N. Y., a corporation of New
Jersey

Application December 17, 1947, Serial No. 792,125

5 Claims. (Cl. 93—6)

1

This invention relates to a method of sealing bags or other flexible containers and has particular reference to a novel method of folding together and sealing marginal edge portions of an open end of a bag filled with articles such as cans or containers. This is a companion application to our copending United States applications Serial Number 792,122, filed December 17, 1947, on Sealing Head mechanism for Closing and Sealing Bags and Containers; Serial Number 792,123, filed December 17, 1947 on Bag Sealing Machine; and Serial Number 792,124, filed December 17, 1947 on Bag Sealing Machine.

An object of the invention is the provision of a method of folding and sealing an open end of a bag or flexible container filled with articles such as cans wherein the marginal edge portions of the bag adjacent its open end are turned or folded inwardly at the corners independently of the intermediate or side portions so as to effect a neat appearing overlapping corner assembly.

Another object of the invention is the provision of such a method wherein the marginal edge portions of the open end of a bag are folded inwardly at the corners in a pleated fashion which results in a smooth corner construction which may be readily sealed when sealing the bag.

Numerous other objects and advantages of the invention will be apparent as it is better understood from the following description, which, taken in connection with the accompanying drawings, discloses a preferred embodiment thereof.

Referring to the drawings:

Figure 1 is a perspective view illustrating the open upper end of a bag filled with cans preparatory to being sealed by method steps embodying the present invention, with parts broken away;

Fig. 2 is a view similar to Fig. 1 showing the bag sealed;

Fig. 3 is a top plan view of a bag being sealed and parts of the apparatus used in sealing the bag;

Fig. 4 is an enlarged sectional view showing a pleated corner fold taken substantially along the line 4—4 in Fig. 2; and

Figs. 5 to 8 inclusive are perspective views showing a fragment at the upper corner of a bag and illustrating how its marginal edge portions are folded and sealed in accordance with the method steps of the present invention, the views illustrating parts of the apparatus in various positions for carrying out the method steps.

As a preferred form of the instant invention, the drawings illustrate method steps of sealing a bag or flexible container A of rectangular cross-

section, preferably made of fibre and filled with cans B for shipment or storage. Bag A at its upper end, is provided with a marginal edge portion C which includes corner sections D and straight side sections E which are folded inwardly against a top sheet or closure member F having a band of adhesive or glue G on its top surface to seal the bag in accordance with the method steps of the invention.

10 In the sealing of the bag A, the closure member F is first inserted into the bag on top of the cans B as shown in Fig. 1. The corner sections D of the marginal edge portions C, are then folded inwardly against the inserted closure member F as shown in Fig. 5. This is followed by the inward folding of the side sections E of the marginal edge portion C, while the corner portions D are held down, the terminal ends of the side sections E overlapping the corner portions D as at J, K (Figs. 4 and 6.)

15 In order to form a smooth corner construction, the overlapped portions J, K now are creased or pressed downwardly against the corner portions D to form corner pleats (Figs. 2 and 4) preparatory to final sealing of the bag. With the corner sections D and side sections E of the marginal edge portion C in this folded over position, they are pressed tightly against the closure member F to insure proper bonding of these parts through the medium of the adhesive or glue G on the closure member. This seals the bag in a neat appearing and strong end construction as best shown in Fig. 2.

20 One form of apparatus for carrying out the sealing of the marginal edge portion C of the bag in accordance with the instant method is a sealing head 10 (Fig. 3) which includes a plurality of corner folding elements 11 and side folding elements 12 carried in a rectangular shaped head frame 13 made to fit over the open top end of a bag to be sealed.

25 The corner folding elements 11 (see also Figs. 5, 6, 7 and 8) are located adjacent the corners of the rectangular frame 13 and are substantially triangular in outline. There are four of these corner folding elements 11, one for each corner of the bag to be sealed. These elements are formed on arms 14 having long hubs 15 mounted on pins 16, carried in bearing lugs 17 which project inwardly from the head frame 13. The corner folding elements 11 are rocked on their pins 16 simultaneously and toward and away from the bag, in any suitable manner.

30 When the corner folding elements 11 rock inward or toward the bag A, they engage the corner

sections D of the marginal edge portion C of the bag, and bend and fold them inwardly and downwardly against the adhesive coated portion of the closure member F, as best shown in Fig. 5. The corner folding elements remain in this position and hold the corner sections D in their folded over position while the side sections E of the marginal edge portion C of the bag are folded into position.

The side folding elements 12 provided for folding in the side sections E, are located along the sides of the head frame 13. There are four of these side folding elements and they are formed on arms 21 having long hubs 22 which are mounted on pins 23 carried in bearing lugs 24 projecting inwardly from the head frame 13. These side folding elements are rocked simultaneously on their pins 23, in any suitable manner toward and away from a bag in the sealing head 10 in time with the other moving parts of the head.

When the side folding elements 12 rock toward the marginal edge portion C of the bag they engage and fold the side sections E inwardly and downwardly against the adhesive coated portion of the closure member F and hold these side sections E in this position, as best shown in Fig. 6. Following this movement of the side folding elements 12 and while they hold the side sections E of the bag in their folded-in position, the corner folding elements 11 are lifted or swung upwardly into a position as best illustrated in Fig. 7, and thus release their hold on the folded corner portions D. The corner folding elements 11 thereafter are swung inwardly and downwardly a second time and this repeated action of the elements presses flat and creases the overlapped portions J, K of the side sections E and thus produces a neat flat corner pleat as best shown in Figs. 2 and 4.

The folding elements 11, 12 remain in position against the folded marginal edge portion C and thus hold or clamp this edge portion in engagement with the closure F for a predetermined period of time, depending upon the setting time of the adhesive being used, to insure proper bonding of the parts together. This seals the bag.

If desired this holding operation may be effected by an auxiliary clamp member or sealing pad 31 (Figs. 3 and 8) which may be moved into clamping position against the folded marginal edge portion C, in any suitable manner. The pad is designed to fit freely within the area defined by the inner edges of the folding elements 11, 12 as best shown in Fig. 3 and thereby permits of the positioning of the pad while the folding elements are in clamping position. As soon as the pad is in place the folding elements may be lifted out of the way, as best shown in Fig. 8, in readiness for the folding operations on a subsequent bag. The pad may be removed when the glue is set. This completes the bag sealing operations.

It is thought that the invention and many of its attendant advantages will be understood from the foregoing description, and it will be apparent that various changes may be made in the steps of the process described and their order or accomplishment without departing from the spirit and scope of the invention or sacrificing all of its material advantages, the process hereinbefore described being merely a preferred embodiment thereof.

We claim:

1. A method of folding the ends of tubular members for containers, which comprises folding in and holding corner sections of a marginal edge

portion of a tubular member adjacent and surrounding an open end thereof, folding in and holding side sections of said marginal edge portion intermediate said corner sections while continuing to hold said corner sections, said corner sections and said side sections being arranged in lapped relation, releasing said hold on said corner sections while continuing to hold said side sections and pressing said folded corner and said folded side sections together.

2. The method of folding and sealing bags, flexible containers and the like filled with articles, comprising folding in corner sections of a marginal edge portion surrounding the open end of a bag against an inserted closure member, holding said corner sections in their folded-in positions, folding in side sections of said marginal edge portion against said closure member intermediate the adjacent held corner portions and overlapping said folded-in corner sections, releasing said hold on said folded-in corner sections and simultaneously holding said side sections in their folded-in position overlapping the corners, and pressing said folded corner sections and said overlapping folded side sections together against said closure member and securing them thereto to seal the bag and to form pleats at the corners of the bag.

3. The method of folding and sealing bags, flexible containers and the like filled with articles such as cans, comprising folding in and holding corner sections of a marginal edge portion surrounding the open end of a bag against an inserted closure member, folding in side sections of said marginal edge portion against said closure member intermediate adjacent corner sections to form corner pleats, releasing said hold on said folded-in corner sections and simultaneously holding said side sections in their folded-in position, creasing said corner pleats, and pressing said folded corner sections and said folded side sections together and against said closure member and securing them thereto to seal the bag.

4. The method of folding and sealing bags, flexible containers and the like filled with articles such as cans, comprising folding in corner sections of a marginal edge portion surrounding the open end of a bag against an inserted closure member having an adhesive applied thereto, holding said corner sections in their folded-in position against said closure member, folding in side sections of said marginal edge portion intermediate the adjacent held corner sections against said closure member and against said corner sections in overlapping relation thereto, releasing said hold on said folded-in corner sections and simultaneously holding said side sections in their folded-in overlapping relation on said corner sections, and simultaneously pressing said folded-in corner and said folded-in side sections against said closure member to seal the bag.

5. The method of folding and sealing bags, flexible containers and the like filled with articles such as cans, comprising folding in corner sections of a marginal edge portion surrounding the open end of a bag against an inserted closure member having an adhesive applied thereto, holding said corner sections in their folded-in position against said closure member, folding in side sections of said marginal edge portion intermediate adjacent corner sections against said closure member and against said corner sections to form corner pleats, releasing said hold on said

folded-in corner sections and simultaneously holding said side sections, creasing said corner pleats inwardly from said corners and simultaneously continuing said holding of said side sections, and simultaneously pressing said folded-in corner and said folded-in side sections against said closure member to seal the bag.
